UNITED STATES PATENT OFFICE.

CHARLES L. RAYFIELD, OF CHICAGO, ILLINOIS, ASSIGNOR TO BENEKE MANUFACTURING COMPANY, OF CHICAGO, ILLINOIS, A CORPORATION OF ILLINOIS.

COMPOUND VENTURI CARBURETOR.

Application filed October 28, 1922. Serial No. 597,457.

This invention relates to a compound Venturi carburetor having few moving parts and capable of adjustment for best performance over a wide range of speeds.

5 It is an object of this invention to provide a carburetor that can be adjusted to give a progressively richer mixture as the throttle is closed, thereby meeting the requirements for satisfactory performance of 10 an internal combustion engine.

It is a further object of this invention to provide a carburetor free from the requirements of manual adjustment after the 15 adjusting means have been set for the best performance of the engine to which the carburetor is attached.

It is an important object of this invention to provide an improved carburetor having a 20 fixed venturi for the intermediate speed ranges and a movable venturi for the higher speed and load requirements.

It is a further important object of this invention to provide a compound fuel 25 nozzle, the main nozzle of which is controlled by the movable venturi and the other nozzle by the throttle in such a way that as the demand on the carburetor increases the second nozzle will have its fuel supply restricted as the main nozzle is 30 opened.

Other and further important objects of this invention will be apparent from the disclosures in the drawings and specification.

35 The invention (in a preferred form) is illustrated on the drawings and hereinafter more fully described.

On the drawings:
Figure 1 is an elevation of my carburetor 40 with parts shown in section.

Figure 2 is a top plan view of the same.
Figure 3 is a section at right angles to 45 Figure 1 on the center line of the mixing chamber.

Figure 4 is an enlarged sectional detail of the compound nozzle shown in Figure 1.

Figure 5 is a detail of the needle valve for regulating the gasoline feed to the intermediate speed nozzle.

50 Figure 6 is a sectional view on the line 6-6 of Figure 3.

As shown on the drawings:
The body of the carburetor of this invention comprises a float chamber 1, an air inlet 55 chamber 2, a mixing chamber 3, and a

dash pot chamber 4. Attached to the upper end of the mixing chamber 3 is a member 5^a carrying the butterfly throttle valve 5 and a flange 6 to mate with the flange on the intake manifold of the motor. Fuel is supplied to the float chamber through a strainer 7. The float chamber mechanism and the gasoline strainer do not comprise part of the present invention and are so well known that no description thereof is considered necessary.

A centrally apertured partition 8 is formed between the mixing chamber 3 and dash pot 4. A vertical tube 9 supported over the aperture forms the outer or intermediate speed nozzle and is held to the partition by an inner vertical tube 10, forming the high speed nozzle, which has a threaded connection 11 at the top engaging with the tube 9. These tubes have flanges 12 and 13 engaging on the top and bottom of the partition boss 14 and forming a chamber or well 15 within said boss 14. The external diameter of the tube 10 is less than the internal diameter of tube 9 forming a passage 16 from the well 15 up to the threaded connection 11. A plurality of passages 17 are provided in tube 9 leading outwardly into the mixing chamber just below the threaded connection 11.

85 A small venturi 18 is secured around the tube 9 to cause suction on the passages 17. One side of this venturi is cut away below the jets to allow admission of air from the chamber 2, which passes up the annular passage 19 surrounding the tube 9. The venturi has outward passages 20 at its throat corresponding in position to the passages 17 in tube 9 to permit a portion of the fuel spray to pass therethrough when the throttle is 90 completely closed. This venturi is provided with an outwardly extending apron 21 which will be referred to hereinafter.

95 The inlet of air for high speed is controlled by a Venturi tube 22 slidable in the mixing chamber and normally seated on the apron 21 of the small venturi 18 at low and intermediate speeds, thereby preventing the flow of air through the large venturi 22. The venturi 22 is cast with thin walls for 100 lightness so that the outside takes the form of the inside and guide fins 22^a are formed thereon to properly center said venturi in the mixing chamber. The venturi is made 105 light so that the suction of the air drawn 110

up will tend to lift the venturi and allow air to pass therethrough around the apron 21 on the small stationary venturi 18. The large venturi is prevented from rotation by 5 a bifurcated point set screw 23 which engages one of the fins 22^a. Secured in the upper end of the venturi 21 is a transverse member 24 supporting an apertured internally threaded boss 25 in the center of the 10 outlet of the venturi. Extending upwardly in said boss is an externally threaded portion 26 of a metering pin 27 which passes through the outlet of the tube 10 and controls the outlet of fuel therefrom by means 15 of a tapered portion 28 on said pin. An extension 29 of said pin passes downwardly through said tube and the lower end thereof is secured to a plate 30 on the lower side of the dash pot piston 31 slidably mounted in 20 the dash pot chamber 4. The plate 30 covers a central aperture 32 in the piston 31 and is loosely held to the piston by a member secured to the plate 30 and engaging the top of the piston by means of lugs 33 which 25 are given a slight clearance from the piston so that a downward movement of the venturi and metering pin will move the plate 30 away from the piston allowing escape of the liquid below the piston through the aperture 32. On the other hand, upward movement of the venturi will be hindered by the plate which is then lifted against the piston, sealing the aperture.

The controlling effect of the tapered 35 metering pin 27 is regulated by adjusting its position in regard to the threaded boss 25 which may be effected by removing a closure 34 from the bottom of the dash pot chamber and rotating the piston and extension of the pin. In order that the adjustment may be locked a set screw 25' is inserted in the threaded boss 25 in line with the metering pin so that the set screw may be set up against the head of the pin. 40 Liquid fuel is supplied to the dash pot from the float chamber 1 through the passages 35, 36 and 37 the latter of which opens into the well or recess 38 above the point of the needle valve 39, this recess 38 communicating 45 with the float chamber 1 as shown in dotted lines in Figure 3. The dash pot is thus the source of the fuel supply for the high speed nozzle 10 controlled by the metering pin 28. It will be apparent that 50 the check upon the upward movement of the dash pot piston 31 provided by the plate 30 converts the piston into a pump to increase the flow of fuel through the high speed nozzle thus temporarily giving a richer 55 mixture that is proportional to the suddenness of the demand; in other words, supplying a richer mixture for purposes of sudden acceleration.

The needle valve 39 is mounted in a passage 60 boss 40 on the side of the float cham-

ber. The passage or recess 38 has a smaller passage 41 leading axially therefrom and communicating through passage 42 with the annular well 15 formed by tubes 9 and 10 which feeds the intermediate nozzle 19. The 70 flow of fuel through these passages is controlled by the adjustable spring loaded needle valve 39 which seats on the shoulder formed by passage 41 and recess 38. The butterfly throttle shaft has a cam 43 75 mounted thereon which actuates a bell-crank lever 44 with a bifurcated end engaging around a block 45 upon the needle valve 39 above the cap 46 which closes the recess 38. The cam and bell-crank are arranged to lift 80 the needle valve 39 as the throttle is closed thereby supplying more fuel to the well 15. The block 45 is held on the threaded needle valve stem by a knurled nut 39' which allows adjustment of the lift of the needle 85 valve and which is locked by a detent held in a boss on the block 45.

Two sources of fuel are provided for idling speeds; a passage 47 leading from the dash pot chamber to passage 48 leading 90 up through a boss on the side of the mixing chamber and into the member 5^a where it communicates with a smaller passage 49 opening into the intake passage above the throttle, as shown in Figure 3. The second 95 source consists of a tube 50 leading from the member 5^a down inside the venturi 22 ending near an aperture 20 through the stationary venturi 18 where it picks up a mixture 100 of fuel and air. The upper end of the tube 50 communicates through passages 51 and 52 with the intake passage above the throttle as in the first case.

As shown in the drawings, the air inlet 105 is provided with the usual choker butterfly valve, with the usual arrangement of lever and boss for Bowden wire control.

The operation is as follows:

The tubes 9 and 10 form a compound nozzle wherein the outer tube 9 supplies fuel to the stationary venturi 18 that cares for the intermediate speed range when the large venturi 22 is seated on the apron 21 of the stationary venturi. Under such conditions, the throttle will be partly closed and the cam 43 and bell-crank 44 will have lifted the needle valve 39 thus feeding more fuel through this nozzle. Opening the throttle will partly close the needle valve cutting off most of the fuel to nozzle 9, while the increased suction on the mixing chamber lifts the large venturi 22, the metering pin 28 and the dash pot piston 31 which momentarily ejects a surplus of fuel from the nozzle 10 for accelerating purposes, and thereafter supplies most of the fuel for open throttle operation. The fuel supply through this main nozzle is controlled by the tapered metering pin and the greater the suction 125 on the movable venturi the higher it lifts 130

with consequently greater passage for air and a correspondingly greater amount of fuel is admitted through the increased nozzle opening.

5 As the throttle is closed, the suction below the throttle decreases, allowing the large venturi to drop on the apron 21, cutting off both air and fuel. At the same time, the intermediate nozzle between tubes 9 and 10 10 gets a greater supply of fuel due to the needle valve 39 being raised by the cam and bell-crank, so that the mixture grows richer as the throttle closes. At idling speeds, the suction above the throttle brings 15 the idling well into play providing a still richer mixture.

It is therefore apparent that no adjustments for different speeds and loads will be necessary after the metering pin and needle 20 valve have once been correctly adjusted as the carburetor supplies a richer mixture for low power requirements, thus rendering a choke unnecessary except for starting under severe weather conditions.

25 I am aware that numerous details of construction may be varied through a wide range without departing from the principles of this invention, and I therefore do not purpose limiting the patent granted, otherwise than necessitated by the prior art.

I claim as my invention:

1. In a carburetor, a fuel supply chamber, a dash pot chamber communicating therewith, a mixing chamber, an inner nozzle opening into the mixing chamber and the dash 35 pot chamber, an outer nozzle also opening into the mixing chamber and having a source

of fuel supply independent of that of said inner nozzle, a stationary Venturi member secured to said outer nozzle, a Venturi member 40 slidably mounted in said mixing chamber and surrounding the nozzles and stationary Venturi member, means connected to said slideable venturi for controlling the amount of fuel discharged from said inner 45 nozzle, a piston in the dash pot chamber, and a connection between the fuel controlling means and said piston.

2. In a carburetor, a fuel supply chamber, a dash pot chamber communicating 50 therewith, a fuel outlet well, a needle valve therein, a tubular high speed nozzle in communication with the dash pot chamber, an annular intermediate speed nozzle surrounding 55 the high speed nozzle and in communication with the fuel outlet well, a stationary venturi surrounding the intermediate speed nozzle, a low speed fuel passage between the exterior of said stationary venturi and the discharge side of the throttle valve, 60 passages through said stationary venturi supplying fuel to said low speed passage, a high speed venturi surrounding said stationary venturi and slidably mounted in the mixing chamber, means connected to said 65 slideable venturi for controlling the amount of fuel discharged from said high speed nozzle, a piston in the dash pot chamber, and a connection between the fuel controlling means and said piston. 70

In testimony whereof I have hereunto subscribed my name.

CHARLES L. RAYFIELD.
